(57) **CLAIM**

The ornamental design for a video projector, as shown and described.

DESCRIPTION

FIG. 1 is a top, right front perspective view of a video projector in accordance with my new design;

FIG. 2 is a front elevation view thereof;

FIG. 3 is a rear elevation view thereof;

FIG. 4 is a reduced scale top plan view thereof;

FIG. 5 is a reduced bottom plan view thereof;

FIG. 6 is a right side elevation view thereof;

FIG. 7 is a left side elevation view thereof; and,

FIG. 8 is reduced reference view showing the video projector in one possible state of use.

The broken lines showing portions of a video projector are included for the purpose of illustrating environmental structure and form no part of the claimed design.
